UNITED STATES PATENT OFFICE.

EDWARD STEWART, OF FORT MADISON, IOWA.

IMPROVEMENT IN RUFFLING ATTACHMENTS FOR SEWING-MACHINES.

Specification forming part of Letters Patent No. 136,676, dated March 11, 1873.

To all whom it may concern:

Be it known that I, EDWARD STEWART, of Fort Madison, in the county of Lee and State of Iowa, have invented certain Improvements in Ruffling and Plaiting Attachments for Sewing-Machines, of which the following is a specification:

The nature of the invention consists in a novel combination and arrangement of devices in the construction of a ruffler or plaiting attachment for sewing-machines, whereby the number of plaits in a given distance may be varied, and the number of stitches in each fold may be adjusted with great accuracy.

In the accompanying drawing is represented an attachment adapted to plait, gather, or ruffle a piece of muslin or other like material singly, or to be sewed between two flat fabrics, or to one such only, and in which—

Figure 1 represents a front elevation of my attachment. Fig. 2 is a plan or top view of the same; and Fig. 3, a transverse section taken on the line $x-x$ on Fig. 1.

The same letters occurring on the several figures indicate like parts.

The feeder of the plaiting, gathering, and ruffling attachment is composed of two metallic spring-plates, a b , the ends of which toward the needle converge so as to take a hold on the cloth between them and carry it forward, while in its return motion it will have no bite; one or both of these may be serrated at the forward end. The lower plate b may, if desired, be somewhat shorter than the upper one, and the serrated ends of both plates, which exert a holding gripe on the cloth, may be curved, their front ends being notched to permit the passage of the needle. These spring-plates or grippers are attached to a reciprocating plate, A , which slides back and forth on the bed-plate B , which latter is attached to the cloth-table of the machine. On the bed-plate B , in rear of the reciprocating plate A , is erected a standard, C , for the support of the operating mechanism, which latter consists of a ratchet-wheel, D , operated intermittently by a slotted lever, E , connected with the needle-bar of the machine, and which lever communicates reciprocating motion to the plate A through the levers G and H . G is a rigid part of the lever E , arranged about at

right angles thereto, and it enters a slot in the lever H , which is arranged transversely beneath the plate A , and is pivoted at the rear of the standard C . The reciprocating motion is communicated to said plate A by the lever H , which strikes the pawl v in its forward motion, and the adjustable arm r in its backward motion. This arm r is pivoted to the plate A , as at z , from which point on the upper side of said plate A projects an arm, z' , which engages with a segmental rack, y , by which the position of the arm r and the consequent throw of the plate A is regulated. To the plate A is attached the spring feeding or ruffling plates a b , the forward end of one or both of which is notched where the needle passes. The ratchet-wheel D is operated by the vibration of the slotted lever E connected with the needle-bar through the spring-pawl p , and is retained during the upward motion of the needle-bar by the spring-pawl q ; the pivoted levers n arranged on the face of said ratchet-wheel operate by means of projections x from their face side. The piece t or feed-regulator is pivoted in lugs on the plate A , and carries the pawl v , through which the forward movement of the plate A is communicated, and it is held toward the ratchet-disk D with the pawl v elevated by a spring. Now, when these projections x come in contact with the back of the piece t , the pawl v , through which the forward motion of the ruffler is communicated, is depressed, and the plates a b are moved forward. The number of plaits in a given distance may be varied by the number of these lever projections x brought into use during each revolution of the disk D , the slotted lever E at the several notches of the ratchet-wheel between said projections x operating the pawl without operating the plate A ; but when it is desired to make a stitch between each motion of the ruffler-feed, the vibrating piece t may be locked by the hook or button s being turned over the front-edge portion of its bed u , as represented in dotted lines in Fig. 2, so that by using one, two, or all of the levers u , the number of stitches in each plait may be either three, six, or twelve, or any other number, according as the ratchet-disk D is divided on its periphery.

I am aware that ruffling attachments have

been heretofore constructed in which the number of stitches in each plait was variable; this, therefore, I do not claim, broadly; but

What I do claim, and desire to secure by Letters Patent, is—

1. The combination and arrangement of the levers *n*, provided with lateral projections *x*, with the feed-regulator *t*, substantially as shown and described.

2. The combination of the pawl *v* with the feed-regulator *t* and actuating-lever *H*, for operation as set forth.

EDWARD STEWART.
